UNITED STATES PATENT OFFICE.

HENRY MÜLLER, OF PHILADELPHIA, PENNSYLVANIA.

FRAUD-DETECTOR.

1,192,095.

Specification of Letters Patent. Patented July 25, 1916.

Application filed August 19, 1914. Serial No. 857,459.

To all whom it may concern:

Be it known that I, HENRY MÜLLER, a citizen of the United States, residing at Philadelphia, in the county of Philadelphia and 5 State of Pennsylvania, have invented certain new and useful Improvements in Fraud-Detectors, of which the following is a specification.

My invention relates to improvements in 10 fraud detectors, the object of the invention being to provide improved means for showing at a distance the entire operation of a cash register, so that the proprietor of a business can, in another room, not only observe 15 the employee, but can have before him an accurate reproduction of the operation of the cash register, so that he can instantly detect fraud of any kind.

A further object is to provide an improved 20 attachment for cash registers which can be installed on any ordinary cash register having upwardly projected indicators which show the amount of the purchase, and which remain in an elevated position until the cash 25 register is operated again to project upwardly other indicators as is well understood.

With these and other objects in view, the 30 invention consists in certain novel features of construction and combinations and arrangements of parts as will be more fully hereinafter described and pointed out in the claims.

In the accompanying drawings: Figure 1 35 is a view in section showing a building having a bar room on the first floor and an office or proprietor's room on the second floor showing how the proprietor in the room above can observe the entire operation of the 40 business in the room below. Fig. 2 is an enlarged view in front elevation partly broken away illustrating the improved electric indicator which is controlled by the operation of the cash register. Fig. 3 is a view partly 45 in end elevation and partly in vertical transverse section illustrating my improved attachment in connection with an ordinary type of cash register. Fig. 4 is a view in section looking upwardly, said view being 50 taken on the line 4—4 of Fig. 3. Fig. 5 is a perspective view illustrating two series of my improved electric contacts. Fig. 6 is a view in cross section on the line 6—6 of Fig. 2, and Fig. 7 is an electric diagram illustrating 55 my improved electrical connections.

1 represents a building which contains on

the first floor, a bar room 2 and on the second floor, an office room 3 for the proprietor. While I have referred to these rooms as a bar room and an office room respectively, 60 the invention is not limited to this particular use, as it may be used in connection with any business, and the rooms may be located at various positions relative to each other and at various distances apart without departing 65 from my invention, and I have chosen these terms merely for convenience of description.

In the bar room 2, a cash register 4 is located, and on the wall of this room, a clock 70 5 or other suitable inclosure is shown. In the clock 5, a mirror 6 is provided which is so positioned as to reflect the operations of the bartender so that he may be clearly observed by the proprietor in the room 75 3 above. To facilitate the view, a tube 7 is provided which registers with an opening 8 in the floor 9, and is in line with the mirror 6, so that the proprietor seated upon the chair 103 in front of desk 11, can by a 80 glance through the tube 7, observe the actions of the bartender.

The particular arrangement of the tube, is of course to be varied in accordance with the 85 location, and it may assume any angle or be used without any mirror if the location of the hole 8 is such as to permit the observation without any mirror, hence I do not limit myself to the particular arrangement of the tube, nor to the particular location of the 90 mirror, as these features of my invention will be varied to suit conditions.

On top of the desk 11, I provide an improved electric indicator 12 which consists of a casing divided by vertical and horizontal partitions 13 and 14 into a plurality of compartments 15. Each compartment contains an electric lamp 16, and a transparent cover 17 closes all of the compartments, and is provided in front of each compartment 100 with a numeral 18, as many of such compartments and numerals being provided as there are indicators 19 on the cash register 4.

The cash register 4 is of the ordinary type having upwardly movable indicators 19 105 which contain numerals thereon, and which are elevated when the keys 20 are depressed to show the amount purchased.

Inside of the casing of the cash register, I locate a bar 21 which is of metal or other 110 conducting material suitably insulated from the casing and held in horizontal position

as clearly shown. On the under face of this bar 21, I secure a bar 22 of insulation, and to this bar 22, I secure a series of movable electric contacts. These electric contacts are 5 arranged in several series of three contacts to a series, and the contacts of each series vary in length, hence for convenience of description I will give the contacts of each series different reference characters. The 10 shortest contacts of each series I give the reference numeral 23, the next longer contacts 24, and the longest contacts 25. These contacts are preferably of very fine spring wire or other thin metal, and are secured 15 by binding posts 26 to the bar 22. Each contact is bent downwardly as shown at 27, and then extends forwardly as shown at 28, so that each indicator 19 can operate but a single contact, and it is to be understood, of 20 course, that the contacts will be so arranged that they will be above the several indicators, and the elevation of any indicator will cause the contact above the same to be elevated to close an electric circuit, as each contact will 25 have a stationary contact 29 above the same.

To insure a proper electric contact, I preferably form the contacts 29 with V-shaped recesses 30 in downwardly projecting tongues 31 thereon at their free ends; and 30 these recesses 30 receive the contacts 23, 24, or 25 as the case may be, and hold the contacts against lateral displacement. The contacts 23, 24, and 25 are sufficiently elastic and flexible to allow for varying movements 35 of the indicators, and to insure a perfect electric contact as long as the indicator remains in its upwardly projecting position.

The parts above described are to be constructed as small as possible, and are to be 40 located within the cash register to make them inconspicuous so as not to excite suspicion, and by reason of the construction above described, I may attach my improvements to any ordinary cash register.

45 In Fig. 7, I illustrate an electric diagram showing a simple form of electric circuit which reduces wiring to a minimum. In this diagram, it will be noted that the battery or source of electricity supply 32 is connected at one side by a wire 33 with the bar 21 to which all of the stationary contacts 29 are secured. The movable contacts 23, 24, and 25 are connected by wires 34 with the lights 16, and the latter are connected to a common return wire 35 which connects to the other side of the battery or source of electricity supply 32.

When any of the contacts 23, 24, or 25 are

moved into engagement with other fixed contacts, the circuit is closed, and the proper 60 light is included in its electric circuit to illuminate the numeral in the transparent cover 17, hence the proprietor knows exactly what key of the cash register has been depressed, and as he can observe the actions 65 of his employee and knows exactly what is going on in the room, he can tell without fail whether or not the business is being honestly conducted.

By reason of my improvements, the 70 cheapest forms of cash register can be used, and the proprietor will know of a surety whether or not any fraud is being perpetuated upon him.

Various slight changes might be made in 75 the general form and arrangement of parts described without departing from my invention, and hence I do not limit myself to the precise details set forth, but consider myself at liberty to make such changes and 80 alterations as fairly fall within the spirit and scope of the appended claims.

Having thus described my invention, what I claim as new and desire to secure by Letters Patent is:

85

1. A cash register in combination with an indicator remote therefrom, means for actuating said indicator upon operation of the cash register, and means for reflecting the image of the cash register to a point adjacent said indicator, substantially as described.

2. The combination with a cash register having movable indicators, of an electric indicator located at a distance from the cash 95 register, a metal bar in the upper portion of the cash register and insulated therefrom, a bar of insulation secured to the metal bar, a series of movable contacts secured to the bar of insulation, said movable contacts having their free ends bent downwardly and projected forwardly and positioned over the indicators, stationary contacts secured to the first-mentioned bar, each stationary contact having a recess in its free end to receive the 100 movable contact, and an electric indicator included in electric circuits with said contacts and a source of electricity supply, substantially as described.

105 In testimony whereof I have signed my name to this specification in the presence of two witnesses.

HENRY MÜLLER.
